UNITED STATES PATENT OFFICE.

PAUL I. ANDERSON, OF DES MOINES, IOWA, ASSIGNOR TO BLACKHAWK TIRE & RUBBER COMPANY, OF DES MOINES, IOWA.

DESIGN FOR A NON-SKID TIRE.

54,193.

Specification for Design.

Patented Nov. 18, 1919.

Application filed August 20, 1919. Serial No. 318,823. Term of patent 14 years.

To all whom it may concern:

Be it known that I, PAUL I. ANDERSON, a citizen of the United States, and a resident of Des Moines, in the county of Polk and State of Iowa, have invented a certain new, original, and ornamental Design for a Non-Skid Tire, of which the following is a specification, reference being had to the accompanying drawing, forming part thereof.

Figure 1 is a plan view; and Fig. 2 is a side elevation showing my new and ornamental design of a non-skid tire.

I claim:

The ornamental design for a non-skid tire, as shown.

Des Moines, Iowa, August 7, 1919.

PAUL I. ANDERSON.
